CORE CATCHER

George F. Grimmelmann, Los Angeles, Calif., assignor to Globe Oil Tools Company, Los Nietos, Calif., a corporation of California

Application February 15, 1936, Serial No. 64,068

17 Claims. (Cl. 255—72)

This invention relates to a well tool and relates more particularly to a core catcher for use in a core barrel or well core drill. A general object of this invention is to provide a simple practical and particularly dependable core catcher.

Another object of this invention is to provide a core catcher embodying core gripping slips that cannot foul the core. A popular form of core catcher now in general use embodies gripping slips carried by spring fingers and the core entering the drill often fouls these slips and becomes broken up or distorts and breaks the spring fingers. The core catcher of the present invention embodies core gripping slips whose inward movement is definitely limited so that they cannot foul the core.

Another object of this invention is to provide a core catcher embodying core gripping slips and pivoted core gripping dogs carried by a rigid body or ring so that there is little or no danger of their loss or failure.

Another object of this invention is to provide a core catcher embodying slips pivotally mounted in the core catcher body in such a manner that rotation of the core catcher with the drill during drilling operations tends to free the slips from the core in the event that they have prematurely engaged the core.

Another object of this invention is to provide a core catcher embodying pivoted or swingable slips mounted in the core catcher body in a novel and particularly effective manner.

Another object of this invention is to provide a core catcher of the character mentioned embodying a floating ring mounted in the core drill for free rotation and provided with an inclined surface against which the pivoted slips bear for actuation against the core. The slips of the core catcher bearing on a free floating ring do not cause or tend to cause the core catcher to rotate with the drill whereby the core catcher may remain nonrotatable during the rotary drilling to score or mutilate the core to a minimum extent.

Another object of this invention is to provide a core catcher that is operable to receive and retain a full sized unmutilated core.

Another object of this invention is to provide a core catcher that is strong and long wearing and that does not embody parts subject to failure or distortion through contact with the core.

The various objects and features of my invention will be fully understood from the following detailed description of a typical preferred form and application of my invention, through-

out which description reference is made to the accompanying drawings, in which:

Fig. 1 is a side elevation of a core drill with a lower portion broken away to illustrate the core catcher of the present invention arranged therein. Fig. 2 is an enlarged plan elevation view of the core catcher with a portion broken away to appear in horizontal cross section being a view taken substantially as indicated by line 2—2 on Fig. 3. Fig. 3 is a side elevation of the core catcher with a portion broken away to appear in vertical cross section being a view taken substantially as indicated by line 3—3 on Fig. 2. Fig. 4 is a fragmentary plan view of the core catcher showing one of the slips in the actuated position. Fig. 5 is a fragmentary vertical detailed sectional view showing an actuated slip bearing on the floating ring. Fig. 6 is an enlarged fragmentary vertical detailed sectional view taken substantially as indicated by line 6—6 on Fig. 2 and Fig. 7 is a fragmentary horizontal sectional view taken substantially as indicated by line 7—7 on Fig. 6.

The core catcher of the present invention is capable of embodiment in forms for use in various types and classes of core barrels or core drills. In the following detailed disclosure I will describe one typical form and application of the invention, it being understood that the invention is not to be construed as limited or restricted to the specific form and details about to be described.

The core drill illustrated in the drawings comprises an outer barrel 10 whose upper end is adapted to be connected with a rotary drilling string. A tubular connecting member or sub 11 is threaded on the lower end of the outer barrel 10 and a bit head 12 is threaded to the lower end of the sub 11. The bit head 12 is tubular being provided with a central vertical opening 13 for receiving the core. Cutting means are provided on the head 12 for making an annular cut in the earth formation. In the case illustrated in the drawings roller cutters 14 are rotatably supported in pockets 15 in the lower end of the head 12 to make an annular cut in the earth formation and leave a core for reception in the opening 13. The sub 11 is provided adjacent its lower end with an internal upwardly facing shoulder 16 and a sleeve 17 fits on this shoulder 16 to extend upwardly in the sub. In practice the sleeve 17 may be welded to the sub 11 at the shoulder 16. The sleeve 17 is spaced from the interior of the sub 11 leaving an annular passage 18 for the circulation fluid. Spaced or ported parts 19 project

from the interior of the sub 11 to engage the sleeve 17 adjacent its upper end and operate to support and centralize the sleeve.

An inner barrel 20 extends longitudinally 5 through the outer barrel 10 to receive the core formed by the cutters 14. A bearing member 21 is fixed to the lower end of the inner barrel 20 and has a shoulder 22 adapted to rotatably bear on the upper end of the sleeve 17 to rotatably 10 support the inner barrel 20 in the outer barrel 10. The bearing member 21 projects into the sleeve 17 and its lower end presents a downwardly facing shoulder 23 in the sleeve. The sleeve 17 has an upwardly facing internal shoulder 24 15 spaced some distance below the shoulder 23. The inner barrel 20 is spaced from the interior of the outer barrel 10 leaving an annular passage 25 for the downwardly flowing circulation fluid. Ports 26 are provided in the bearing member 21 20 and communicate with the lower end of the passage 25 and the upper end of the passage 18. Ports 27 and 28 extend downwardly through the sub 11 and the bit head 12 from the lower end of the passage 18 to the pockets 15 to carry the 25 circulation fluid to the pockets where it discharges against the cutters 14.

The core catcher of the present invention includes, generally, a floating ring 29 arranged in the sleeve 17 between the shoulders 23 and 24, a ring or body 30 extending through the ring 29, pivoted dogs 31 on the body 30, and pivoted slips 32 on the body 30 operable by engagement with the ring 29 to grip a core extending through the tool.

35 The ring 29 is provided in the sub sleeve 17 between the shoulders 23 and 24 and is freely rotatable therein whereby it may remain non-rotatable during rotation of the drill. The ring 29 forms a wedge element or actuating abutment for the 40 slips 32. The internal surface 33 of the ring 29 is inclined downwardly and inwardly, being shaped for engagement by the slips 32 as will be hereinafter described. The inclined surface 33 may extend substantially the entire length of the 45 ring 29 as illustrated in the drawings. The abutment ring 29 being positioned between the shoulders 23 and 24 is constrained to move vertically or longitudinally with the outer barrel 10 and sub 11.

50 The body 30 forms a support or carrier for the dogs 31 and the gripping slips 32. The body 30 of the core catcher is in the nature of a tube or ring and is arranged axially or longitudinally in the sub sleeve 17. The body 30 may be of substantial length and may extend longitudinally 55 through the ring 29. In accordance with the invention the body 30 is a floating element free to remain non-rotatable during the rotary drilling operations. The core catcher body 30 may be 60 integral, however, it has been found practical to form the body 30 in two sections, 34 and 35. The section 34 is the main or principal section of the body 30 and the section 35 is a ring-like part telescoping over the lower portion of the section 65 34 and projecting downwardly from the lower end of the section 34. The opposing and engaging surfaces of the sections 34 and 35 are provided with annular opposing grooves registering to form an annular opening 36 which is concentric 70 with the longitudinal axis of the body 30. The body sections 34 and 35 may be detachably connected by rivets 37 or the like, which may pass through the opening 36 as clearly shown in Fig. 2 of the drawings. The internal diameter of the 75 body 30 is substantially the same as the core re-

ceiving opening 13 of the head 12. A plurality of circumferentially spaced windows or openings 38 is provided in the wall of the body 30 to receive the dogs 31. The openings 38 are substantially rectangular and intersect the annular opening 36. 5

The dogs 31 are provided to assist in gripping and retaining the core and act to resist movement of the body 30 relative to the core when the drill is moved upwardly to actuate the slips 32. The dogs 31 are pivotally supported in the openings 38 10 on pins 39 whose end portions are carried in the annular opening 36. The end portions of the pins 39 may be flattened as shown in Fig. 2 of the drawings to cooperate with the walls of the opening 36 to prevent rotation and longitudinal movement of the pins. The dogs 31 pivoted on the pins 39 are adapted to pivot downwardly and inwardly in the interior of the body 30 to bite into the core. The active ends or edges 40 of the dogs 31 are 15 pointed or sharpened to readily cut into the core. If desired, the dogs 31 may be of different lengths as shown in the drawings. In the form of the invention disclosed some of the dogs 31 are relatively long to be capable of gripping and retaining soft under-sized cores, some of the dogs 31 20 are of medium length to dependably bite into medium hard cores, while certain of the dogs 31 are relatively short to dependably grip hard full-sized cores. Means are provided for urging the dogs 31 into cooperation with the core. Slots 41 25 are provided in the outer ends of the dogs 31 and torsional springs 42 are provided in the slots 41 and are wrapped about the pivot pins 39. The springs 42 bear against the body section 35 and the dogs 31 to urge the dogs downwardly and 30 inwardly against the core.

The character, mounting and operation of the slips 32 are features of the invention. The slips 32 are carried by the core catcher body 30 above the dogs 31 and are operable through cooperation 40 with the inclined surface 33 to tightly grip and retain the core. Openings 44 are provided in the wall of the body 30 to receive the slips 32. The openings 44 are spaced above and in offset relation to the dog receiving openings 38. In the 45 preferred construction the openings 44 are rectangular being elongated circumferentially of the body 30. The slips 32 are substantially rectangular members proportioned to fit the openings 44 with substantial clearance. The inner 50 or active faces of the slips 32 are provided with wickers or teeth 45 to bite into and retain the core.

In accordance with the invention the slips 32 are supported to pivot or swing about axes which 55 are substantially parallel with the longitudinal axis of the core drill. A substantially vertical opening 46 is provided in the rear portion of each slip 32 relative to the direction of rotation of the drill. Pins 47 extend through the openings 60 46 and have their end portions carried in openings 48 in the body 30 to pivotally support the slips 32. The slip carrying pins 47 are preferably stationary or fixed. In the structure shown in the drawings the upper portions of the pins 65 47 are threaded in the openings 48. The upper and lower sides of the slips 32 may have bearing bosses or lugs 49 bearing outwardly against the walls of counterbores 50 in the openings 48. The slips 32 mounted as just described are capable of swinging about substantially vertical axes 70 between positions where they are substantially retracted in the openings 44 as shown in Fig. 7 to positions where they project into the body 30 as shown in Fig. 4 to grip the core.

Each slip 32 has a surface 52 on its outer side for cooperating with the inclined surface 33 of the floating ring 29. The surfaces 52 of the slips 32 are curved to conform to the surface 33 and are inclined downwardly and inwardly to evenly bear on the surface. Means are provided for yieldingly urging the slips 32 outwardly to have cooperation with the surface 33 and to normally remain in their retracted positions where they do not engage the core. Horizontal slots 53 are provided in the inner or rear ends of the slips 32 and intersect the openings 46. Torsional springs 54 are wrapped about the pins 47 in the slots 53 and bear on the slips 32 and the body 30 to urge the slips outwardly to have their surfaces 52 cooperate with the surface 33. The invention provides means for definitely limiting the inward movement of the slips 32. Stop lugs 55 are provided on the outer or forward ends of the slips 32 and are adapted to cooperate with recesses 56 in the body 33 to positively limit the inward swinging of the slips 32. This definite limiting of the inward travel of the slips 32 is important as it prevents the slips from fouling the core.

During operation the outer barrel 10 is connected with the rotary drilling string and is rotated and fed downwardly in the well so that the cutters 14 cut into the earth formation to form the core for reception in the drill. Circulation fluid is continuously pumped downwardly through the strip to flow through the passages 25 and 18 and the ports 27 and 28 and discharge against the cutters 14. The slips 32 are normally urged outwardly against the inclined surface 33 by the springs 54 while the dogs 31 are urged inwardly to positions such as illustrated in the drawings. As the drill moves downwardly over the core the dogs 31 engage the upper end of the core as it enters the body 30. This engagement of the dogs 31 with the core tends to hold the body 30 stationary relative to the rotating and downwardly moving drill. Accordingly, the engagement of the dogs 31 with the core tends to hold the body 30 stationary while the ring 29 moves downwardly with the drill. The resulting relative movement between the ring 29 and the slips 32 results in the full retraction of the slips under the action of the springs 54. In this manner, the slips 32 are fully retracted before they reach the upper end of the core. The retracted slips 32 do not in any way interfere with the core and do not mutilate or groove the core. The engagement of the dogs 31 with the core may be sufficient to hold the body 30 against rotation with the drill so that the core is not subjected to a cutting action or scoring action by the core catcher. The inner barrel 20 is operable to receive the core when it emerges through the core catcher.

When it becomes desirable to recover or remove the core the drill is moved upwardly to actuate the core catcher. The engagement of the dogs 31 with the core holds or substantially holds the body 30 against upward movement with the drill so that the upward movement of the drill results in relative vertical movement between the surfaces 33 and 52. The surfaces 33 and 52 cooperate during this relative vertical movement to swing or pivot the slips 32 inwardly into gripping contact with the core. The slips 32 may be forced inwardly through the cooperation of the surfaces 33 and 52 until they obtain a firm hold on the core. Upward movement of the drill also usually causes the dogs 31 to obtain firmer and deeper engagement with the core. Con-

tinued upward movement of the drill results in the breaking of the core from the earth formation. The slips 32 and the dogs 31 biting into the core support and retain the core for withdrawal from the well.

The core catcher of the present invention is such that it cannot foul or destroy the core. The lugs 55 positively limit the inward movement of the slips 32 so that the slips cannot assume positions where they materially interfere with the passage of the core into the inner barrel. The ring 29 having the slip actuating surface 33 is free to float in the sleeve 17 so that the engagement of the slips 32 with the ring does not force or cause the core catcher body 30 to turn with the drill. The parts are assembled and related so that there is a minimum amount of friction between them. The core catcher body 30 may remain non-rotatable during the drilling and the dogs 31 and the slips 32 have little or no tendency to groove or cut into the core.

Having described only a typical preferred form and application of my invention, I do not wish to be limited or restricted to the specific details herein set forth, but wish to reserve to myself any variations or modifications that may appear to those skilled in the art or fall within the scope of the following claims:

Having described my invention, I claim:

1. In a core drill having an inclined internal surface, the combination of, a body in the drill, and a member carried by the body to swing inwardly about an axis substantially parallel with the longitudinal axis of the drill through cooperation with the inclined surface.

2. In a core drill having an inclined internal surface, the combination of, a body arranged in the drill for relative longitudinal movement, a core gripping member, and means supporting the member on the body to swing about a substantially vertical axis through cooperation with said surface.

3. In a core drill having an inclined internal surface, the combination of, a body arranged in the drill for relative longitudinal movement, a core gripping slip on the body swingable inwardly about a substantially vertical axis through cooperation with said surface, and means on the body having movement resisting cooperation with the core whereby vertical movement of the drill actuates the slip.

4. In a core drill having an inclined internal surface, the combination of, a body arranged in the drill for relative vertical movement, a pivoted dog on the body operable to engage a core to resist movement of the body, and a core gripping slip pivoted on the body to swing about a substantially vertical axis and engaging said surface whereby the surface actuates the slip upon relative vertical movement between the drill and body in one direction.

5. A core catcher for a core drill comprising, a ring to be arranged in the drill for vertical movement therewith, the ring having an inclined surface, a body to be arranged in the drill for relative vertical movement, core gripping slips, and means pivotally supporting the slips on the body for pivotal movement about substantially vertical axes and to pivot inwardly through cooperation with the inclined surface upon relative vertical movement between the drill and body.

6. A core catcher for a core drill comprising, a ring to be arranged in the drill for vertical movement therewith, the ring having an inclined surface, a body to be arranged in the drill

- for relative vertical movement, a core gripping slip means pivotally mounting the slip on the body to turn about a substantially vertical axis and to have cooperation with the inclined surface, and yielding means holding the slip in cooperation with the said surface.
7. A core catcher for a core drill comprising, a ring to be arranged in the drill for vertical movement therewith, the ring having an inclined surface, a body to be arranged in the drill for relative vertical movement, a core gripping slip pivoted to the body to swing about a substantially vertical axis, yielding means holding the slip in cooperation with the said surface, and means for resisting vertical movement of the body whereby the slip is actuated by vertical movement of the drill.
8. In a core drill having a barrel with spaced internal shoulders, the combination of, a ring arranged between the shoulders for free rotation and for vertical movement with the barrel, a floating body in the barrel, and a pivoted core gripping slip pivoted on the body to swing inwardly about a substantially vertical axis through cooperation with the ring.
9. In a core drill having a barrel with spaced internal shoulders, the combination of, a ring arranged between the shoulders for free rotation and for vertical movement with the barrel, the ring having an inclined surface, a shiftable and freely rotatable body in the barrel, and a core gripping slip pivoted on the body to swing about a substantially vertical axis through cooperation with said inclined surface.
10. In a core drill having a barrel with spaced internal shoulders, the combination of, a ring arranged between the shoulders for free rotation and for vertical movement with the barrel, the ring having an inclined surface, a body arranged in the barrel for relative shifting and rotation, means on the body cooperable with the core to resist movement of the body, and a pivoted core gripping slip on the body actuated through cooperation with said inclined surface to swing about a substantially vertical axis.
11. In a core drill having a barrel with spaced internal shoulders, the combination of, a ring arranged between the shoulders for free rotation and for vertical movement with the barrel, the ring having an inclined surface, a body arranged in the barrel for relative shifting and rotation, and a core gripping slip pivoted to the body for swinging movement about a substantially vertical axis and having an inclined surface for cooperating with the inclined surface of the ring.
12. A core catcher for use in a core drill comprising, an annular body for arrangement in the drill, the body having an opening in its wall, a core gripping slip, and means pivotally supporting the slip on the body for swinging through the opening about an axis substantially parallel with the longitudinal axis of the body.
13. A core catcher for use in a core drill comprising, an annular body for arrangement in the drill, the body having a lower opening in its wall and an upper opening in its wall, a core engaging dog pivoted in the lower opening, and a core gripping slip pivoted in the upper opening to swing about an axis substantially parallel with the longitudinal axis of the body.
14. A core catcher for use in a core drill comprising, an annular body for arrangement in the drill, the body having a lower opening in its wall and an upper opening in its wall out of vertical alignment with the lower opening, a core engaging dog pivoted in the lower opening, and a core gripping slip pivoted in the upper opening to swing about an axis substantially parallel with the longitudinal axis of the body.
15. A core catcher for use in a core drill comprising, an annular body for arrangement in the drill, the body having a lower opening in its wall and an upper opening in its wall, a core engaging dog pivoted in the lower opening, a core gripping slip pivoted in the upper opening to swing about an axis substantially parallel with the longitudinal axis of the body, means urging the slip outwardly, and a member movable vertically with the drill and having an inclined surface for operatively engaging the slip.
16. A core catcher for use in a core drill comprising, an annular body for arrangement in the drill, the body having an opening in its wall, a core gripping slip, means pivotally supporting the slip on the body for swinging through the opening about a substantially vertical axis, and means limiting inward swinging of the slip.
17. A core catcher for use in a core drill comprising, an annular body for arrangement in the drill, the body having an opening in its wall, a core gripping slip, means pivotally supporting the slip on the body for swinging through the opening about a substantially vertical axis, and means limiting inward swinging of the slip, the last named means comprising, a lug on the slip for engaging the body.

GEORGE F. GRIMMELSMAN.
